UNITED STATES PATENT OFFICE.

CHARLES E. CHAPMAN, OF FORT EDWARD, NEW YORK, ASSIGNOR, BY MESNE ASSIGNMENTS, OF ONE-HALF TO ROBERT C. CARTER AND GEORGE S. JAMISON, BOTH OF GLENS FALLS, NEW YORK.

CLOSURE FOR CLEAN-OUT OPENINGS.

Original application filed October 16, 1923, Serial No. 668,833. Divided and this application filed October 16, 1925, Serial No. 62,852. Renewed May 25, 1927.

This invention relates to an improved closure for clean out openings, being a division of my co-pending application for welding torch burner, filed October 16, 1923, Serial No. 668,833.

The invention seeks, among other objects, to provide a closure which, while being especially adapted for use in connection with welding torch burners, will also be well adapted for general use, and wherein freezing of the closure will be eliminated, so that, when desired, the closure may be easily and quickly removed.

The invention seeks, as a further object, to provide a closure which will effect a sealed joint to fluid at high pressure and which will be adapted to withstand high temperatures.

And the invention seeks, as a still further object, to provide a closure which will be of simple construction, wherein metal to metal contact will be had between the sealing plate employed and the wall of the clean out opening, and wherein clamping means will be provided for pressing the plate against said wall to mutilate the plate to conform to the contour of the opening and form a protected sealed joint between the parts.

Other objects of the invention not specifically mentioned in the foregoing, will appear during the course of the following description.

In the accompanying drawings:

Figure 1 is a vertical longitudinal sectional view taken through the burner disclosed in my prior application identified and showing the closure in connection with the burner.

Figure 2 is a sectional view on the line 2—2 of Figure 1, looking in the direction indicated by the arrows.

Figure 3 is a detail perspective view of a typical sealing plate.

Referring now more particularly to the drawings, I have shown my improved closure in connection with a burner of the character illustrated in my prior application previously identified, and in order that the function of the closure may be better understood, it is well to generally describe the burner. This burner includes a mixing

chamber 10 carrying an apertured burner plate 11, and screwed over one end of said chamber is a cap 12 from which projects a spider 13 carrying a ring 14. Screwed through the end wall of the cap to extend horizontally within the mixing chamber is a draft tube 15, and screwed into the ring 14 is a valve casing 16 having a discharge orifice 17 disposed opposite the open outer end of said tube. The casing mounts a valve 18 which is adjustable for regulating flow through said orifice and communicating with the orifice is a passage 19 in the valve casing. Extending above the mixing chamber 10 in parallel relation thereto are generating tubes, one of which is shown at 20. The tube 20 is connected with the valve casing 16 to communicate with the passage 19 of said casing and liquid fuel is supplied to the generating tubes so that as the fuel flows through said tubes, the fuel will be vaporized by the heat of the flame rising from the burner plate 11, the fuel gases being conducted through the passage 19 of the valve 16 casing to the orifice 17 to be injected into the draft tube 15 and thence enter the mixing chamber 10 to rise through the burner plate.

In the practical use of burners of this character, it is frequently found necessary to clean out the generating tubes as well as clean out the vapor conducting passage of the valve casing and it, therefore, becomes necessary to provide a removable closure for the tubes as well as said passage. As will be appreciated, a like necessity is often encountered in the practical use of burners of types other than that illustrated in the present instance as well as in connection with various other apparatus, and the present invention, therefore, seeks to provide a closure which will efficiently fulfill the requirements. As is well known, clean out plugs are prevalently used for the purpose and these plugs are screwed into position. However, as is well known, when such a plug is subjected to heat, the plug freezes in position with the result that it becomes extremely difficult to remove the plug and fracture or injury of the parts often result in the attempt. The present improvements accordingly further seek to eliminate this difficulty. In the

drawings, I have shown one of the improved closures in connection with the valve casing 16 as well as in connection with the tube 20. However, since both closures are identical, 5 only one will be described in detail, and since the valve casing as well as the tube provides a duct, the closure structure will be described in conjunction with a duct. Like reference characters are applied to 10 similar parts of both closures illustrated.

Coming now more particularly to the subject of the present improvements, the element or duct to which the closure is applied is integrally formed or otherwise equipped 15 with a bonnet 21 which extends over the clean out opening of the duct, and screwed through the bonnet is a clamp screw 22 extending axially of the duct. Overlying the clean out opening of the duct is a flexible 20 sealing plate 23 which is preferably formed of copper or a metal softer than the metal of the duct, and as will be observed, the screw 22 is adjusted to tightly clamp said plate against the end edge of the wall 25 of the duct. The screw is of a diameter substantially equal to the internal diameter of the duct and is rounded at its inner end to project into the duct so that when the screw is adjusted to clamp the sealing plate, 30 the sealing plate is bowed into the duct and is sheared more or less between the inner end of the screw and the end edge of the wall of the duct so that the plate is thus mutilated at the surface thereof which contacts the edge of the wall of the duct to 35 conform to said edge and provide a protected joint between the plate and duct sealing the duct. Experience has shown that the joint thus formed will, in practical use, 40 not only withstand fluids at high pressure but will also withstand relatively high temperatures. The importance of these factors in a burner of the character illustrated will 45 be at once appreciated when it is considered that the closure is more or less directly subjected to the action of the flame at the burner plate 11. To remove the sealing plate, the clamp screw 22 is retracted when, by 50 tapping on the sealing plate, said plate may be easily and quickly released and removed, when the duct may be cleaned through the clean out opening thereof.

Having thus described the invention, what I claim is:

1. In a burner, the combination with an 55 element provided with a passage having a clean out opening, a flexible plate overlying said opening, and means pressing the plate into the opening to seal said opening.

2. In a burner, a duct having a clean out 60 opening, metallic sealing means overlying said opening and having metal to metal contact with said duct for withstanding a high temperature, and means clamping said sealing means in position closing said opening. 65

3. In a burner, a duct having a clean out 70 opening, flexible sealing means overlying said opening, and clamping means bowing said sealing means into the opening for closing said opening.

4. In a burner, a duct having a clean out 75 opening and provided with a bonnet, a flexible plate overlying said opening, and a clamp screw screwed through the bonnet and bowing the plate into said opening for closing the opening.

5. The combination with an element having 80 a clean out opening, of a flexible sealing plate overlying said opening, and means flexing the plate into said opening and clamping said plate in position whereby the plate is tensioned against said element to form a gas-tight seal for said opening.

6. The combination with an element having 85 a clean out opening, of sealing means adapted to be sheared against the wall of said element for sealing said opening, and retaining means for said sealing means.

7. The combination with an element having 90 a clean out opening, of sealing means overlying said opening, and means clamping said sealing means in position and shearing said means against said element to seal said opening.

8. The combination with a metallic element having a clean out opening, of a metallic sealing plate overlying said opening and mutilated at its point of contact with said element for sealing said opening, said sealing plate being composed of a metal softer than the metal of said element, and retaining means for said plate. 95

In testimony whereof I affix my signature,
CHARLES E. CHAPMAN. [L.S.]
